UNITED STATES PATENT OFFICE.

ALEXANDER T. KASLEY, OF SWISSVALE, PENNSYLVANIA, ASSIGNOR TO WESTINGHOUSE ELECTRIC & MANUFACTURING COMPANY, A CORPORATION OF PENNSYLVANIA.

PROPELLER.

1,372,295.

Specification of Letters Patent.

Patented Mar. 22, 1921.

Application filed March 31, 1917. Serial No. 158,867.

To all whom it may concern:

Be it known that I, ALEXANDER T. KASLEY, a citizen of the United States, and a resident of Swissvale, in the county of Allegheny and State of Pennsylvania, have made a new and useful Invention in Propellers, of which the following is a specification.

This invention relates to propellers and has for an object to produce a new and improved propeller especially adapted to be employed in driving torpedoes.

A further object is to produce a folding propeller which may be employed in apparatus where it is desired to at times decrease the amount of space occupied by the propeller.

A further object is to produce a folding propeller which will automatically unfold and assume an operative position when it is rotated or when it strikes the water.

These and other objects are attained by means of a propeller herein described and illustrated in the drawings accompanying and forming a part hereof.

25 In the drawings: Figure 1 is a diagrammatic view, partly in section, of a propeller embodying my invention.

Fig. 2 is an end view of the movable blade shown in Fig. 1.

30 Fig. 3 illustrates a pair of propellers in the folded position as carried by a torpedo in passing through a torpedo tube, and, in the dotted lines, in the unfolded operative position.

35 It is impractical to provide a torpedo with a keel, or to so lower the center of gravity that the torpedo will not rotate when driven by a single impeller. Therefore torpedoes have commonly been provided with two propellers operating about the same axis and in opposite directions. This construction necessitates the use of hollow shafts and other expensive parts. Furthermore, it is necessary to provide a rudder supporting 40 structure around the propellers which limits their size and consequently their effective area, while in my invention the total effective blade area may be considerably increased, with a corresponding increase in the speed of the torpedo.

45 The use of two propellers operating about different axes has been objectionable because they project sidewise beyond the body of the torpedo, if they are of a reasonable size, 50 and therefore they cannot pass through the

torpedo tube. This difficulty is overcome in my invention by providing each impeller with a folding blade which enables the torpedo to be passed through the tube and which will automatically open out and assume an operative position as soon as the torpedo clears the tube or strikes the water.

In my invention each propeller operates in undisturbed water and therefore at the highest efficiency. With the old construction the maximum speed of a torpedo has been limited by the inefficient propellers and their limited area, but as this discrepancy has been overcome by my invention, the speed may be increased considerably. The two propellers when unfolded operate in the same manner as those of a twin screw ship and are therefore capable of the same high efficiency.

55 In Fig. 1, I have illustrated a propeller shaft 5 carrying on its outer end a propeller embodying my invention. As shown, the propeller is made up of two parts 6 and 7. The part 6 comprises a blade 8 and a hub 9. In this embodiment of my invention the hub 60 9 is preferably secured to the propeller shaft by means of a key 10. The inner part 7 of the propeller is provided with a hub 11 and a blade 12. I have shown this hub as provided with threads 13, which engage similar 80 threads 14 on the propeller shaft 5. The face of the hub 11 adjacent to the hub 9 is provided with teeth 15, which are adapted to engage with similar teeth 16 on the hub 9 and to lock the movable blade 12 in an 85 operative position. These teeth are also shown in Fig. 2.

90 In Fig. 3, I have illustrated two propellers in the folded position as carried by a torpedo while passing through a torpedo tube 17. In order to prevent the torpedo from rotating in the water, the two propellers are preferably operated in opposite directions, as indicated by the arrows. After the torpedo is discharged from the torpedo 95 tube, the force of the water on the movable blades 12 causes them to lag behind the other blades and to assume the operative position indicated by the dotted lines, where they are locked by the engagement of the 100 teeth 15 and 16.

105 It is evident that this construction is cheap and easy to manufacture, as no hollow shafts or complicated parts are necessary. Furthermore, the propeller is very simple 110

and substantial. Propellers may be constructed so that after the movable blade 12 has revolved into the operative position, it is firmly wedged there by the threads 13 and 5 14, so that the propeller is as rigid and efficient as a solid propeller.

While I have illustrated and described but one embodiment of my invention, it will be apparent to those skilled in the art that 10 various changes, modifications, additions and omissions may be made in the apparatus illustrated without departing from the spirit and scope of the invention, as set forth by the appended claims.

15. What I claim is:

1. In a propelling device, a propeller shaft, a blade rigidly fixed on said shaft, a blade rotatably mounted on the shaft, engaging means carried by the blades for limiting the travel of the rotatable blade and 20 engaging means on the shaft and carried by the rotatable blade for wedging said rotatable blade in place at the limit of its travel.

2. In a propelling device, a propeller shaft, a blade movably mounted on said shaft, means for causing longitudinal movement of the blade when it is rotated about the shaft, and means for limiting the movement of the blade.

30. 3. A propeller in which at least one blade is fixed on the propeller shaft and a blade is rotatably mounted on the propeller shaft, in combination with means for moving the rotatably mounted blade longitudinally of the shaft to a position substantially in the plane of rotation of the fixed blade and a means for limiting the rotation of the rotatable blade with respect to the fixed blade.

4. A propeller in which at least one blade 40 is fixed on the propeller shaft and one blade is rotatably mounted on the propeller shaft, means whereby relative rotary motion between the blades moves the rotatably mounted blade longitudinally along the shaft to a 45 position, substantially in the plane of rotation of the fixed blade, and means for holding the rotatable blade against rotation in this position.

5. A propeller in which at least one blade 50 is fixed on the propeller shaft, and one blade is movable with relation to the shaft, a screw threaded connection between the movable blade and the shaft whereby the blades are moved toward one another by rotation 55 of one of the blades, and means for limiting the relative rotary movement of the blades.

6. A propeller in which at least one blade is fixed on the propeller shaft and one is movable relatively of the shaft, a screw 60 thread connection between said shaft and the movable blade, and a stop for limiting the motion of the movable blade relatively to the shaft.

7. In combination in a propeller shaft, a 65 plurality of propeller blades, at least one of

which is circumferentially and longitudinally movable with relation to the shaft and means limiting the circumferential and longitudinal movement of the movable blade.

8. In combination in a propeller, a plurality of propeller blades, at least one of which is movable with relation to the shaft, means for causing longitudinal movement of the movable blade when it is rotated relatively to the shaft, and means for limiting 75 the longitudinal and rotative movement of the blade.

9. The combination with a shaft having a fixed propeller blade and a movable blade adapted when in inoperative position to occupy a plane of rotation other than that occupied by the fixed blade and in the operative position to occupy a plane of rotation substantially coincident with that of the fixed blade, of means for moving the movable blade to operative position actuated by 80 relative movement of the shaft and the movable blade.

10. In an automobile torpedo having a plurality of propelling devices rotating about different axes; each of said propelling devices comprising a propeller shaft, a blade rigidly fixed on the shaft, a blade movably mounted on the shaft, and means automatically moving the movable blade into operative position, whereby the propeller blades may in inoperative positions be contained within the space defined by the projection of the torpedo body in the direction of its travel and in operative positions extend beyond 90 said projection of the torpedo body.

11. In an automobile torpedo having a plurality of propelling devices operating about different axes and throughout effective areas extending beyond the space defined by the projection of the torpedo body in the direction of its travel; each of said propelling devices comprising a propeller shaft, one or more blades rigidly fixed on the shaft, a blade rotatably mounted on said shaft, engaging means carried by said blades for limiting the travel of the rotatable blade and engaging means on the shaft and carried by the rotatable blade for wedging said rotatable blade in place at the limit of its travel.

12. In an automobile torpedo having a plurality of propelling devices operating about different axes and throughout effective areas extending beyond the space defined by the projection of the torpedo body in the direction of its travel; each of said propelling devices comprising a propeller shaft, one or more blades rigidly fixed on the shaft, a movable blade, means operatively connecting the movable blade to the shaft so constructed that by movement of the movable blade all blades may be confined within the said projection of the torpedo body, and means automatically mov- 120 125 130

ing the movable blade into operative position.

13. In an automobile torpedo having a plurality of propelling devices operating about different axes and throughout effective areas extending beyond the space defined by the projection of the torpedo body in the direction of its travel; each of said propelling devices comprising a propeller shaft, one or more blades rigidly fixed on the shaft, a rotatable blade means operatively connecting the rotatable blade to said shaft so constructed that by movement of the rotatable blade all blades may be confined within the said projection of the torpedo body, means for moving the rotatably mounted blade longitudinally of the shaft to an operative position substantially in the plane of rotation of the fixed blade or blades and means for limiting the rotation of the rotatable blade or blades with respect to the fixed blade.
14. In an automobile torpedo having a plurality of propelling devices operating about different axes and throughout effective areas extending beyond the space defined by the projection of the torpedo body in the direction of its travel; each of said propelling devices comprising a propeller shaft, one or more blades rigidly fixed on

the shaft, a rotatable blade mounted on the shaft, means whereby relative rotary motion between the blades moves the rotatably mounted blade longitudinally along the shaft to an operative position, substantially in the plane of rotation of the fixed blade or blades, and means for holding the rotatable blade against rotation in this position.

15. In an automobile torpedo having a plurality of propelling devices operating about different axes and throughout effective areas extending beyond the space defined by the projection of the torpedo body in the direction of its travel; each of said propelling devices comprising a propeller shaft, one or more blades rigidly fixed on the shaft, a blade circumferentially and longitudinally movable with relation to the shaft, means limiting the circumferential and longitudinal movements of the movable blade, and means for holding the movable blade in operative position.

In testimony whereof I have hereunto subscribed my name this 30th day of March, 1917.

ALEXANDER T. KASLEY.

Witnesses:

C. W. McGHEE,
M. B. GORDON.

It is hereby certified that in Letters Patent No. 1,372,295, granted March 22, 1921, upon the application of Alexander T. Kasley, of Swissvale, Pennsylvania, for an improvement in "Propellers," errors appear in the printed specification requiring correction as follows: Page 3, line 21, claim 13, strike out the words "or blades"; same page and claim, line 22, after the word "blade" insert the words *or blades*; and that the said Letters Patent should be read with these corrections therein that the same may conform to the record of the case in the Patent Office.

Signed and sealed this 3d day of May, A. D., 1921.

[SEAL.]

T. E. ROBERTSON,

Commissioner of Patents.
